UNITED STATES PATENT OFFICE.

ERNEST J. TURNER, OF PITTSBURGH, PENNSYLVANIA, AND BLOOMFIELD H. HOWARD,
OF WASHINGTON, DISTRICT OF COLUMBIA.

FEEDER FOR INGOT MOLDS.

Application filed December 23, 1921. Serial No. 524,460.

To all whom it may concern:

Be it known that ERNEST J. TURNER and BLOOMFIELD H. HOWARD, citizens of the United States, residing, respectively, at 5 Pittsburgh, county of Allegheny, State of Pennsylvania, and city of Washington, District of Columbia, have invented certain new and useful Improvements in Feeders for Ingot Molds, of which the following is 10 a specification.

Our invention relates to improvements in feeders for ingot molds.

The object of our invention is to provide a feeder for ingot molds which has a certain amount of flexibility, and yet at the same time having the necessary strength to withstand the strain of the molten metal thereon, and should it crack, it will not separate and allow the molten metal to flow 20 therefrom.

Another object of our invention is to provide means whereby the same can be manufactured with the thinnest possible walls practical to maintain sufficient heat to prevent piping, segregation and the like in order to save material in the manufacture thereof, and also saving in weight in transportation, and yet maintaining the strain of the molten metal and at the same time 25 providing a feeder which can be used on molds of slightly varying sizes.

A further object of our invention is to provide a simple, cheap and effective feeder of this character having certain details of structure and combinations of parts hereinafter more fully set forth.

In the accompanying drawings—

Fig. 1 is a perspective view of the upper end of an ingot mold showing our improved 40 feeder applied thereto.

Fig. 2 is a top plan view of Fig. 1.

Fig. 3 is a top plan view of a modified form.

Fig. 4 is a side elevation, partly in section 45 of a still further modified form.

Fig. 5 is a perspective view of a still further modified form of retaining member for the feeder.

Fig. 6 is a perspective view of another 50 modified form of retaining member.

Fig. 7 is a perspective view of another modified form of retaining member.

Fig. 8 is a vertical sectional view showing another form of feeder.

Fig. 9 is a vertical sectional view showing another form of feeder.

Fig. 10 is a vertical sectional view similar to Fig. 9, showing the retaining member turned upside down, and wedges used to tighten same.

Fig. 11 is a top plan view of another modified form.

Fig. 12 is a side elevation of Fig. 11, and

Fig. 13 is a sectional view showing the retaining member extending into the upper 65 end of the mold.

Referring now to the drawings, 1 represents the ingot mold which, as shown, is of any ordinary form, and into which fits the feeder 2 which is provided with the ribs 3, 70 which rest upon the upper end of the ingot mold and prevents the feeder from passing into the mold beyond a certain point. In feeders of this character, in order to save material and also weight in transportation, 75 the walls between the ribs are made comparatively thin, and it sometimes happens that these walls give way under the tension and weight of the molten metal before it hardens and allows the metal to flow over 80 the mold and is wasted, and which forms a defective ingot. In order to strengthen the feeder we provide a member made in two sections 4 and 5 hinged together at 6, and having at their outer free ends the outward 85 turned hooked ends 7 and 8, which are obliquely arranged, and over which fits the wedge shaped locking member 9, which has inwardly turned ends adapted to interlock with the outwardly turned ends 7 and 8 and 90 draw them together to cause the member to tightly bind around the feeder and strengthen the same. By this arrangement it will be seen that the feeder, should it crack, would not separate and allow the 95 metal to flow therefrom.

In Fig. 3 instead of having the two sections hinged together, both ends are provided with the hooks and locked together by the wedge shaped members 10 and 11 100 constructed exactly like the locking member 9 of the form shown in Figs. 1 and 2.

In the form shown in Figures 4 and 5 the strengthening or reinforcing member instead of being a plain, narrow band are 105 provided with the downwardly extending apron portions 12, 13, 14, 15, 16 and 17, which engage the thin walls of the feeder

between the ribs and give a greater support thereto to prevent them from crumbling under the tension and weight of the molten metal of the ingot. In this form, the wedging or locking member 18 is constructed the same as that shown in Figures 1 and 2, and the operation is the same.

In Figure 6 instead of having the two sections hinged, as shown in Figures 1 and 2, the two sections of the reinforcing member are made L-shaped, and hinged together at the corner as indicated at 19, and the fastening means 20 is arranged at the corner. In this form there are provided the four downwardly extending apron portions 21, 22, 23 and 24 arranged for the purpose described in respect to Figures 4 and 5.

In Fig. 7 we have provided a band made solid which has upwardly extending arms 24', 25, 26 and 27 having their upper ends turned inwardly as indicated at 28, and which extend over the upper end of the feeder and supports the same, and which like in the other forms, prevents the spreading or separating of the feeder should it crack.

In the form shown in Fig. 8 we provide a plane continuous metal member 29 of an internal diameter slightly greater than the external diameter of the feeder and tightly clamped thereon by the wedges 30.

In Figure 9 the internal wall of the band 31 is slightly tapering, as indicated at 32 and which allows of its insertion over the upper end of the feeder, and allows it to be tightly driven down into the position shown in Fig. 9.

In Figure 10 the same member is employed, but it is inverted, and wedges 33 are employed to lock the same on the feeder, and whereby the same member can be used on feeders of slightly varying sizes.

In Figures 11 and 12 we have shown the feeder 34 of a slightly different form, and the member 35 is made of a shape to correspond thereto, and being made of a single piece of metal having its ends secured together by the clamping member 36 constructed the same as that shown in Figures 1 and 2.

In Figure 13 we have shown the aprons 50 carried by the bands, as shown in Figures 4 and 5, and extending into the upper end of the mold, and whereby the apron is supported or held against outward movement

and the feeder more firmly held in place should it crack under the heat or strain of 55 the molten metal.

Claims.

1. A feeder for ingot molds comprising a tubular body portion of refractory material and a removable reusable metal reinforcing 60 member around the same.

2. A feeder for ingot molds comprising a tubular body portion of refractory material, ribs projecting outwardly, and a removable metal reinforcing member extending around 65 the same and closely embracing the contour of the body portion and the ribs.

3. A feeder for ingot molds comprising a tubular body portion of refractory material having ribs projecting outwardly therefrom, 70 a removable metal reinforcing member around the same, and tightening means for said member to cause it to closely hug the outer portion of the feeder.

4. A feeder for ingot molds comprising a 75 tubular body portion of refractory material, a band encircling the same, downwardly extending holding aprons carried by said band and adapted to closely fit the walls of the feeder.

5. A feeder for ingot molds comprising a tubular body portion of refractory material, a band removably secured around the feeder, and downwardly extending holding aprons carried by said band and adapted to closely 85 fit the walls of the feeder.

6. A feeder for ingot molds comprising a tubular body portion of refractory material, ribs projecting outwardly adjacent its upper end, a band removably secured around the 90 feeder and ribs, and aprons carried by the band and extending below the ribs and entering the upper end of the mold.

7. A feeder for ingot molds comprising a tubular body portion of refractory material, 95 ribs projecting outwardly adjacent its upper ends, a band around the feeder, means for tightening said band, and downwardly extending holding aprons carried by said band and formed integral therewith and adapted 100 to closely fit the walls of the feeder.

In testimony whereof we affix our signatures.

ERNEST J. TURNER.
BLOOMFIELD H. HOWARD.
